UNITED STATES PATENT OFFICE

114,121

DESIGN FOR A CLOCK

Paul M. Klein, Cedarhurst, N. Y.

Application July 14, 1938, Serial No. 78,473

Term of patent 7 years

To all whom it may concern:

Be it known that I, Paul M. Klein, a citizen of the United States and resident of Cedarhurst, in the county of Nassau, State of New York, have invented a new, original, and ornamental Design for a Clock, of which the following is a specification, reference being had to the accompanying drawing, forming part thereof, and in which

Fig. 1 is a top view of the clock, and

Fig. 2 is an elevation thereof, showing my new design.

The characteristic features of the present design consist of a clock movement operated globe suspended in a vertical hoop, which latter is supported by a base, and an indicator ring surrounding the globe about its equator.

I claim:

The ornamental design for a clock, as shown and described.

PAUL M. KLEIN.
